UNITED STATES PATENT OFFICE.

JOHN SELLERS BANCROFT AND MAURITZ C. INDAHL, OF PHILADELPHIA, PENNSYLVANIA, ASSIGNORS TO LANSTON MONOTYPE MACHINE COMPANY, OF PHILADELPHIA, PENNSYLVANIA, A CORPORATION OF VIRGINIA.

COMPOSING-MACHINE FOR RECORD-STRIPS.

1,094,631.

Specification of Letters Patent. Patented Apr. 28, 1914.

Application filed May 21, 1913. Serial No. 769,015.

To all whom it may concern:

Be it known that we, JOHN SELLERS BANCROFT and MAURITZ C. INDAHL, citizens of the United States, residing at Philadelphia, 5 in the county of Philadelphia and State of Pennsylvania, have invented certain new and useful Improvements in Composing-Machines for Record-Strips; and we do hereby declare the following to be a full, 10 clear, and exact description of the same, reference being had to the accompanying drawings, forming part of this specification, and to the figures and letters of reference marked thereon.

15 This invention relates to improvements in record strip composing machines for use in connection with automatic type casting and composing machines equipped with supplemental mold adjusting means for adding extra spacing to the produced type, and it has 20 for its principal object to provide a simple and effective means whereby such spacing can at will be applied to single type.

Heretofore the supplemental spacing mechanism of the casting machine has been controlled through either the justifying space signal or the justification signal components as illustrated in Patents No. 952,633 of March 22, 1910, and No. 1,042,476 of October 29, 1912. According to the first of said 25 patents the extra spacing component is associated with the justification space signal and operates to connect a mechanism responding to said space signal with shifting devices controlled by the extra spacing component for shifting an extra spacing member alternately into and out of operative connection with the mold adjusting devices. 30 Inasmuch as the justifying space signal is an essential component of the extra spacing signal, only type occurring intermediate justification spaces can be enlarged. The machine of the second patent is designed to remove this restriction and permit the extra 35 spacing to be applied to any type or syllable between justifying spaces, to which end the actuating devices for the extra spacing member are coupled with the driving mechanism of the casting machine, and the 40 application thereof to said extra spacing member is controlled by the justification designating components in association with a type signal. This involves not only an undue multiplication of signal components and 45 additions to the controlling members for the

extra spacing member of the casting machine, but also the abandonment of the sectional line justification features of the casting machine.

Now it is proposed, according to the present invention, to exercise control of the extra spacing member of Patent No. 1,042,476 through a single special signal-component or perforation, which, when associated with any type signal will operate to apply the extra spacing member, and when omitted will cause the withdrawal of said member or maintain same out of engagement. Thus whenever a signal containing this special component is presented it will add the extra space to the produced type, and when omitted will result in the production of type of normal dimensions.

Although intimately related to the casting machine the present invention pertains more directly to the composing machine and embraces the means whereby the extra component of the type signals is produced and the space value thereof registered on the line measuring mechanism, all as will hereinafter more fully appear.

In the accompanying drawings, illustrating a preferred form of embodiment, Figure 1 is a front elevation of a part of known form of composing machine with the improvements applied thereto. Fig. 2 is a partial transverse vertical section of said machine. Fig. 3 is a perspective view of the added elements shown detached and in conjunction with the series of punch bars. Fig. 4 is a similar view with the connector or interponent engaged and the line rack gaging member advanced.

The same numerals designate like parts in the several views.

The invention is illustrated in its application to the composing machine of Patent No. 944,405, dated December 28, 1909, to which reference is made for a more full disclosure of its construction and operation, it being understood that the only changes are by way of addition. It will suffice for present purposes to identify some of the principal elements of the patented machine, such as the series of thirty one punches and attached punch-bars 1 through which the components of the type, space and justification signals are produced; the units rack 2, units wheel 3 and justification drum 4 of the line measuring mechanism; the key bank

5; and the paper feed 6. Each of the punch bars 1 is coupled with a compressed air motor and each key controls the operation of such of the punch bars,—usually two—as 5 correspond with the signal components pertaining thereto. The punches comprise three groups, one group of fourteen representing successive stages of adjustment of the die case in one direction, a second group representing like stages of adjustment in a direction transverse to the first, and a third group including two justification designating punches and a single space or transfer punch. The final or fifteenth stage of adjustment for each of the fourteen groups is indicated by the absence of any component of that group.

One of the fourteen group of punch bars represents dimensions as well as position, its 20 members being separately coupled to complementary members of a series of stop bars (not shown) which measure the advance of the units rack when engaged with the units wheel of the line measuring mechanism, 25 said units rack normally engaging an abutment or stop 7 which determines the zero or datum line for measuring the excursions of the units rack.

To provide for the new or extra spacing 30 signal component an extra or supplemental punch 10 is added to the series heretofore employed, one not participating in the formation of any of the usual type, space and justification signals and only brought into 35 action in connection with the type or space punches when the extra spacing is to be applied to the indicated type body. Conveniently this extra or supplemental spacing punch 10 is unprovided with a special 40 motor but is arranged to be coupled at will with the type or space punches and to be actuated thereby. To this end punch 10 is provided with shoulders forming an open-sided bearing 11 for the entrance and withdrawal of an interponent 12, and each of 45 the punches 1 pertaining to the type and space components is furnished with a shoulder 13 located beneath or in rear of the path of interponent 12 in its movement toward 50 and from the punches, so that when said interponent is advanced into engagement with punch 10 it will be in position to be engaged by one or more of the punches 1 and transmit motion from the latter to the former.

55 Interponent 12 extends transversely of the series of punches and is supported to move both laterally and longitudinally of said punches, as by pivotally supporting the outer portion thereof upon levers 14, the latter pivotally attached at their opposite or lower ends to the frame. To one or both of said levers 14 is connected a retracting spring 15 and an actuating means, represented by a rod 16 provided with a button 17, and notched, as at 18, to coöperate with

a shoulder on the frame for retaining the interponent in its forward or engaging position.

When it is desired to produce the extra spacing signal the actuating devices for interponent 12 are manipulated or set to engage the interponent with the punches before pressure is applied to the key corresponding with the desired type so that when the signal representing said type is produced 75 punch 10 will be actuated to apply the extra spacing signal component. The addition of this extra spacing to the type would seriously interfere with the correct action of the line measuring mechanism if the additional space was not registered thereon, and to permit this to be done, the oscillatory support for the interponent 12 is provided with a stepped gage 20 disposed between abutment 7 and units rack 2 in the line of movement of the latter. The contacting surfaces of gage 20 are displaced by an amount equal or proportional to the space to be added to the type, and said surfaces are so disposed that the thicker portion of the gage stands 80 normally in line with the units rack when interponent 12 is retracted, and when the latter is engaged, the narrower portion of the wedge will be interposed to enlarge the stroke of the units rack by an amount corresponding with space added to the type. The shoulder intermediate the two gaging surfaces is inclined to facilitate movement of the gage while the units rack is retracted. 95

The operation will be readily understood. 100 When the retaining devices represented by notch 18 are released, as by the tilting of rod 16, interponent 12 is automatically retracted, punch 10 rendered inoperative and gage 20 shifted to interpose its major width 105 between the zero stop and the units rack. The composing machine is now in position to operate as usual for the production of type, space and justification signals. When a letter, word or paragraph is reached to 110 which it is desired to add the extra spacing, interponent 12 is moved to operative position and gage 20 shifted to permit longitudinal displacement of the units rack, after which the key or keys representing the type 115 to which the extra spacing is to be applied is or are actuated in the order of composition, with the result that the punch or punches representing the distinguishing signal components, together with punch 10 representing the extra spacing component will 120 be simultaneously operated. At the conclusion of the extra spaced matter the retaining devices are released and interponent 12 is withdrawn to cut out extra spacing punch 10. 125

It should be stated that in the casting machine of Patent No. 1,042,476, the extra spacing component of the type signals operates directly upon the double pawl controlling motor, eliminating the mechanism through 130

which the justification signal components are made to operate said motor in the aforesaid patented structure.

Having thus described our invention what we claim as new and desire to secure by Letters Patent of the United States is,—

1. In a composing machine such as described provided with a plurality of punches for producing the component members of type, space, and justification signals, and in combination therewith, a supplemental punch collocated with the other punches to produce a special signal component in association with those derived from the other punches, and an interponent for coupling said supplemental punch with the series of punches for transmitting motion from the members of the series of said supplemental punch.
2. In a composing machine such as described provided with a series of key controlled punches representing the different components of type, space, and justification signals and in combination therewith, a supplemental punch representing an added space component, and controllable means for coupling said supplemental punch with the members of the first named series of punches so that the latter when actuated for the production of type and space signals, will produce in association therewith the extra space component.
3. In a composing machine such as described provided with a series of type and space signal component punches and a line measuring mechanism for registering the space value of the dimensioning components, including a zero stop and a units rack, and in combination therewith, an extra-spacing component punch, an interponent for coupling said last named punch with the type signal component punches to act in unison therewith in the production of the indicated signal, and a stepped gaging member interposed between the zero stop and units rack and coupled to move in unison with said interponent.
4. In a composing machine such as described equipped with a series of separately movable motor-actuated type signal component punches and a line measuring mechanism, and in combination therewith, an extra-spacing component punch associated with the type-signal component punches, a movable interponent for coupling said extra-spacing and type-signal component punches, and means for varying the action of the line measuring mechanism to compensate for the difference in the space value of the produced signals when said extra-spacing signal component punch is engaged.
5. In a composing machine such as described, and in combination with the series

of type and space signal component punches thereof each provided with an engaging shoulder, of an associated extra-spacing component punch, a two way movable interponent for coupling the shoulders of the type signal component punches and said extra-spacing signal component punch, to cause the latter to operate in connection with any one or more of the operating associated punches, and controllable means, including latching devices, for actuating said interponent.

6. In a composing machine such as described and in combination with its series of independent type signal component punches and line measuring mechanism, the latter provided with a movable admeasuring member and a zero stop therefor, of an extra-spacing signal component punch associated with said type-signal punches, an interponent for temporarily coupling individual type signal component punches with said extra-spacing signal component punch, to operate the latter by the former, and a stepped gaging member interposed between the admeasuring member and zero stop of the line measuring mechanism and coupled with said interponent.

7. In a composing machine such as described provided with a series of independently movable motor actuated type signal component punches, and in combination therewith, an extra spacing signal component punch associated with said series of punches and provided with an opensided bearing, a series of engaging shoulders one for each type signal component punch, and an interponent adapted to enter the open bearing of said extra spacing punch and extend in front of the bearing of the other punches, said interponent being pivotally connected to supporting means, the latter movable toward and from the punches.

8. In a composing machine provided with a series of independently movable type signal component punches each provided with an engaging shoulder, and in combination therewith, an extra-spacing signal component punch provided with an opensided bearing, an interponent movable laterally and longitudinally of said punches, and a support for said interponent movable laterally of the punches to alternately engage the interponent with and disengage it from the bearing on said extra spacing signal component punch and said shoulders of the type signal component punches.
